(57) **CLAIM**

The ornamental design for a wireless charger, as shown and described.

DESCRIPTION

FIG. 1 is a right and top perspective view of a wireless charger, showing my new design;

FIG. 2 is a front, left, and top perspective view thereof;

FIG. 3 is a rear, right, and bottom perspective view thereof;

FIG. 4 is a front elevational view thereof;

FIG. 5 is a rear elevational view thereof;

FIG. 6 is a left elevational view thereof;

FIG. 7 is a right elevational view thereof;

FIG. 8 is a top plan view thereof;

FIG. 9 is a bottom plan view thereof; and,

FIG. 10 is a right and top perspective view thereof, illustrated in another configuration.

The broken lines in the drawings depict portions of the wireless charger and form no part of the claimed design.
